INVENTOR

Delmar G. Hurd,

By Albert M. Moore,
His ATTORNEY.

UNITED STATES PATENT OFFICE.

DELMAR G. HURD, OF LOWELL, MASSACHUSETTS, ASSIGNOR, BY DIRECT AND MESNE ASSIGNMENTS, TO THE IDEAL BUCKLE MANUFACTURING COMPANY, OF PORTLAND, MAINE.

BUCKLE.

SPECIFICATION forming part of Letters Patent No. 633,137, dated September 19, 1899.

Application filed June 4, 1898. Serial No. 682,517. (No model.)

To all whom it may concern:

Be it known that I, DELMAR G. HURD, a citizen of the United States, residing at Lowell, in the county of Middlesex and Commonwealth of Massachusetts, have invented a certain new and useful Improvement in Buckles, of which the following is a specification.

This invention relates to buckles; and it consists in the devices and combinations hereinafter described and claimed, the object of said invention being to furnish a cheap, easily-operated, and reliable buckle which will not mar or cut the strap to which it is applied and will not require such strap to be perforated for the reception of a pointed tongue.

In the accompanying drawings, Figure 1 is a plan of my improved buckle attached to a strap or belt and connecting the ends of the same, the middle portion of the strap or belt being omitted; Fig. 2, a plan of said buckle detached; Figs. 3 and 4, vertical central longitudinal sections of the outer frame on the line 3 3 in Fig. 2, the binder or inner frame being in side elevation, the buckle being closed in Fig. 3 and open in Fig. 4; Figs. 5 and 6, vertical transverse sections on the lines 5 5 and 6 6, respectively, in Fig. 2; Fig. 7, a side elevation of the buckle and strap shown in Fig. 1; Fig. 8, a central vertical section on the line 8 8 in Fig. 1; Fig. 9, a section similar to Fig. 5, but showing a modification of the means of pivoting the parts of the buckle to each other.

My improved buckle consists of an outer frame A, preferably rectangular, within which is arranged a binder B, which may be a plate or block, but for lightness and economy of material is preferably a frame or skeleton, the side bars b b' of which are pivoted at c c' to the side bars a a' of the outer frame in such a manner that the binder B may rock in said outer frame.

The rocking motion of the binder B is limited, Figs. 1 to 4 and 8, in one direction by a transverse ledge a³ on the inner face of the front bar a² of the frame A, said front bar a² being arranged below the front end or bar b² of said binder, and in the other direction by the keeper or rear bar b³ of said binder strik-

ing upon inclined shoulders a⁴ a⁵, with which the inner faces of the side bars a a' are provided. The binder B is thus allowed to rock only enough to allow the unattached end of the strap D to be passed freely through the buckle between said binder and the front bar 55 of the outer frame A.

The side bars b b' of the binder are represented in Figs. 1 to 4 and 8 as being offset outwardly near their rear ends at b⁴ b⁵ and turned upward into slots a⁶ a⁷, the rear inclined sides 60 of which form the shoulders a⁴ a⁵ above mentioned. The nose or front edge of the front bar b² of the binder is slightly beveled to prevent cutting the strap D.

In use one end of the strap D is attached 65 by any usual means, as by sewing or by a rivet E, Figs. 7 and 8, to the rear bar a⁸ of the frame, and the other end of the strap is passed up between the front bar of the binder and the front bar of the frame A and under 70 the rear bar b⁸, which serves as a keeper for the unattached end of the strap, the space between the offset portions b⁴ b⁵ of the side bars b b' being wide enough to receive any strap which can pass between the side bars 75 of the frame A at the ledge a³. The bending of the strap over the ledge a³ in one direction and over the nose of the binder in the other direction causes those parts to hold the strap, and the upward pressure of the strap against 80 the under side of the bar b⁸ holds the front end of the binder more firmly down upon the strap and forces said strap against the front bar of the frame A and prevents the strap from slipping in the buckle. 85

In Fig. 9 the binder is represented with ears c² c³, made integral therewith and laid in slots a⁹ a¹⁰ in the frame A, and said frame is shown with projections a¹¹ a¹², which may be made to reach above the tops of said slots and may 90 be bent down into said slots over said ears c² c³ to retain said ears therein, the projection a¹¹ being represented as already bent into place, while the projection a¹² is unbent.

The parts of the buckle may be cast, as of 95 malleable iron, and used without machining.

I claim as my invention—

1. The combination of a frame having a

- front bar, provided with a transverse ledge on its inner face and having a rear transverse bar for the attachment of a strap, and a binder pivoted in said frame between the 5 ends thereof and having its nose or front edge arranged above said ledge and having its rear end in front of said rear transverse bar outwardly offset to receive the free end of said strap, above said frame.
- 10 2. The combination of a frame having a front bar, provided with a transverse ledge on its inner face, and a binder, consisting of a skeleton pivoted in said frame between the ends thereof and having its nose or front edge

arranged above said ledge and having its rear 15 end outwardly offset and bent upward to receive a strap of the full width of said nose, the upward pressure of said strap on the rear end of said binder holding said nose down upon the portion of said strap passing between said nose and said ledge.

In witness whereof I have signed this specification, in the presence of two attesting witnesses, this 2d day of June, A. D. 1898.

DELMAR G. HURD.

Witnesses:

ALBERT M. MOORE,
GRACE E. HIBBERT.
